UNITED STATES PATENT OFFICE.

ERNEST L. PERSONS, OF CHICAGO, ILLINOIS, ASSIGNOR TO DAVID J. MOLLOY COMPANY, A CORPORATION OF ILLINOIS.

LOOSE-LEAF BINDER.

Application filed March 26, 1925. Serial No. 18,340.

This invention relates to loose leaf binders, and one of the objects of the invention is the provision of new and improved loose leaf retaining mechanism that is easily manipulated, and to which the leaves or papers may be readily applied.

Another object of the invention is the provision of a new and improved flexible loose leaf retaining member that is comparatively rigid when in operative position within the book case or cover, and which may be readily removed therefrom or attached thereto.

A further object of the invention is the provision of new and improved loose leaf retaining means that will permit the leaves to lie flat on the covers when the book is in open position.

A still further object of the invention is the provision of a loose leaf binder, that is simple but rugged in construction, cheap to manufacture, easily assembled, efficient in operation and that is not likely to become broken, distorted or get out of order.

Other and further objects and advantages of the invention will appear from the following description taken in connection with the accompanying drawings, in which

Fig. 1 is a perspective view of a loose leaf cover or case showing the invention in position therein;

Fig. 2 is a cross-section on line 2—2 of Fig. 1;

Fig. 3 is a cross-section on line 3—3 of Fig. 1, with parts removed;

Fig. 4 is a section on line 4—4 of Fig. 1, with parts broken away;

Fig. 5 is a detail view showing the paper holding member or clip;

Fig. 6 is a vertical section thereof; and

Fig. 7 is an elevation of one of the attaching plugs.

On the drawings, the reference character 9 designates the book back and 10 and 11 the sides or covers, which together form what may be termed the case.

The back 9 comprises the usual outer member or cover 13 and the lining or inner member 14. Interposed between the cover 50 and lining is a stiffener member or back plate 15 to which the loose leaf retainer members or clips 16 are detachably connected. If desired, rivets 20 may be employed to secure the back plate 15 in position. The rivets may be attached before the

inner lining 14 is secured in position over the member 15. Preferably the back plate 15 is made of some rigid material as by being stamped from sheet metal, and curved in cross-section, the convex surface being 60 outward to conform to the back portion of the cover or case. This plate will serve to stiffen the back 9 and hold the same in proper form at all times. The edges of the stiffener member or back plate 15 are provided with curved return bends or flanges 17 in which notches 18, preferably V-shape, are provided as clearly shown, in Fig. 4.

The loose leaf retaining members 16 are adapted to be detachably secured to the return bends or flanges 17. The retaining members or paper holding clips 16 may be of any suitable flexible material. Preferably they comprise a body portion 21 formed of resilient material. In the form of the device selected to illustrate one embodiment of the invention the body portion 21 of the retainer member or clip 16 is in the form of a helical spring. Plugs 22 having reduced portions or necks 23 forming the 80 heads 24 are secured to the ends of the spring as by inserting the ends 25 of the plugs in the ends of the spring. The ends 25 are provided with projections or corrugations for engaging the coils of the spring 85 for retaining the plugs therein.

In applying the retaining members or clips to the stiffener member or back plate 15 one of the necks 23 is placed within one of the notches 18, after which the body portion 21 is curved and the neck 23 at the opposite end is inserted in an opposed notch. The resiliency of the clip or retainer member 16 is sufficient to hold the clip in position.

The lining 14 that extends over the flange 17 need not be cut or pierced at the notches as the resiliency of the retainer or clip 16 will force the necks 23 thereof into engagement with the V-shaped notches.

Two or more of the clips or retainer members 16 may be employed as necessity may require.

By means of this arrangement the paper holding clips are detachably secured to reinforcing member 15 without the aid of screws, bolts or additional attaching means. This is considered an important feature of the invention because it eliminates the trouble and annoyance incident to the use of the 110

present type of paper holding prongs in which the prongs being riveted or otherwise secured to their supports soon become loose or broken.

5 In attaching the leaves to the binder the retainer member 16 is released from one or both sides and after the said member has been inserted through the paper the said member is returned to position as described 10 above.

15 It is thought from the foregoing taken in connection with the accompanying drawings that the construction and operation of my device will be apparent to those skilled in the art, and that various changes in size, shape, proportion and details of construction may be made without departing from the spirit and scope of the appended claims.

20 I claim as my invention:

20 1. In a loose leaf binder, a plate having its longitudinal edges return-bent and provided with notches, a resilient flexible paper-retaining member, and means on each end of said retaining member for detachably engaging said notches for holding said last named member in paper-holding position on said plate, said retaining member assuming the form of a straight element when released.

25 2. In combination, a rigid back member or plate having its longitudinal edges return-bent and provided with opposed V-shaped notches therein, a loose leaf retain-

ing member comprising a close coil spring member normally straight having a head 35 and a reduced portion at each end for engaging said notches for securing said leaves to said plate.

3. In a loose leaf binder, a binder plate having a longitudinal edge return-bent and provided with notches, a plurality of loose leaf retaining members, each of said members comprising a closely wound spiral spring member, means for attaching one end of each spring member to an edge portion 40 of said plate, and heads secured to the opposite ends of said spring members and provided with reduced portions for engaging said notches for holding said retainer members in position for retaining loose leaves 45 thereon.

4. In combination, a pair of side members, a back member comprising an outer and an inner flexible element secured to said side members, a stiff back member between said elements, said back member having return-bent flanges provided with notches therein, a resilient loose leaf retaining member comprising a length of coil spring and means for detachably connecting the ends of said 50 member to the notches in said flanges, said means being held in engagement with said plate by the resiliency of said member.

In testimony whereof I affix my signature.

ERNEST L. PERSONS.
